UNITED STATES PATENT OFFICE.

JEFF N. LAMAR, OF DANNEMORA, NEW YORK.

TRACK STRUCTURE.

1,096,433.

Specification of Letters Patent. Patented May 12, 1914.

Application filed February 4, 1914. Serial No. 816,552.

To all whom it may concern:

Be it known that I, JEFF N. LAMAR, a citizen of the United States, residing at Dannemora, in the county of Clinton and State of New York, have invented certain new and useful Improvements in Track Structures, of which the following is a specification, reference being had to the accompanying drawings.

10 This invention relates to certain improvements in track structures and has relation more particularly to a chair adapted to support a rail and to afford a means whereby such rail may be effectively clamped in 15 operative position.

The invention consists in the details of construction and in the combination and arrangement of the several parts of my improved track structure whereby certain important advantages are attained and the device is rendered simpler, less expensive and otherwise more convenient and advantageous for use, all as will be hereinafter more fully set forth.

25 The novel features of the invention will be carefully defined in the appended claims.

In order that my invention may be the better understood, I will now proceed to describe the same with reference to the accompanying drawings, wherein—

Figure 1 is a view in top plan of a track structure constructed in accordance with an embodiment of my invention; Fig. 2 is a view in side elevation of the device as illustrated in Fig. 1, with the coacting rail shown in section; Fig. 3 is a sectional view taken substantially on the line 3—3 of Fig. 1; Fig. 4 is a sectional view taken substantially on the line 4—4 of Fig. 2; and Fig. 40 5 is a view in elevation, detached, of one form of clamping member herein included, the coacting rail being indicated by dotted lines.

As disclosed in the accompanying drawings, 45 1 denotes a tie which may be of wood or iron as best serves the necessities of practice and on the opposite extremities of which are adapted to be rested a chair, indicated as a whole by A, such chair being provided at its opposite longitudinal sides at substantially the center thereof with the depending lips or flanges adapted to overlie the adjacent portions of the tie and serve as a means for maintaining the same in 50 55 operative position. I also provide the vertically disposed openings 3 through the

chair A through which suitable bolts 4 or the like are adapted to pass, such bolts being also directed through the tie 1 whereby such chair may be effectively clamped to the tie, 60 it being understood that coacting with such bolts 4 are the conventional nuts or burs 5.

The intermediate portion of the chair A is provided with the transverse pocket or recess 6, in which is adapted to be received the base portion 7 of a rail B, while the adjacent marginal portions 8 of the chair are provided with the longitudinally directed slots or channels 9 disposed in offset relation and of a predetermined width and being provided with the aligned elongated slots or openings through which are adapted to be extended the clamping members 10, herein shown as conventional bolts and their coacting nuts or burs which are adapted to 70 75 80 85 90 coact with the clamping members 11 and 12 disposed in the opposed grooves or channels 14. As herein disclosed, the clamping members 11 and 12 are of substantially the same width as the channels or grooves 9 and are adapted to be moved longitudinally thereof so that the engaging faces 15 thereof may be caused to properly engage with the rail B. Intermediate their length, such clamping members 11 and 12 are provided with elongated slots through which the retaining means 10, hereinbefore referred to, are adapted to project, the elongated slots or openings readily permitting such movement of the clamping members 11 and 12 90 as the necessities of practice may require.

As herein disclosed, the proper engagement of the clamping members 11 and 12 with the rail is effected through the medium of the elongated members 16 disposed in the 95 recesses or grooves 17 arranged lengthwise of the chair A across the base of the grooves or channels 9 and across the recess 6 and in communication with a suitable opening 18 disposed through the marginal portions 8, 100 such bolts having relatively opposed ends provided with upstanding projections adapted to engage the lower outer ends of the clamping members 11 and 12 so that endwise movement imparted to the elongated members 16 will result in the requisite engagement of the clamping members 11 and 12 with the rail. The members 16 are of such a length as to project beyond the outer end of the openings 18, such projected 105 110 portions 19 are adapted to be engaged by the retaining or clamping nuts or burs 20

whereby it will be seen that the clamping members 11 and 12 are effectively maintained in proper engagement with the rail.

In order to provide a means whereby the rail B may be effectively maintained against turning, I find it of advantage to form the clamping member 12 with the upstanding extension 21 adapted to bear against the head or wall 22 of the rail and which is thought to operate in a manner which is clearly obvious to those skilled in the art to which my present invention appertains.

From the foregoing, it is thought to be obvious that a track structure constructed in accordance with my invention is of an extremely simple and comparatively inexpensive nature and is particularly well adapted for use by reason of the convenience and facility with which the rails may be applied thereto and the security with which such rails are maintained in operative position and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. In combination with a tie, a chair positioned thereon and having a transverse recess adapted to accommodate the base of a rail, the end marginal portions of such chair being provided with longitudinally disposed channels in communication with the transverse recess and disposed in offset relation, clamping members slidably engaged within the longitudinally disposed channels, each of such longitudinally disposed channels and the transverse recess being provided with a longitudinally disposed channel in communication with suitable openings disposed in the adjacent portions of the end margins of the chair, elongated members disposed through such openings and resting in the longitudinally directed recesses, such mem-

bers being adapted to operatively engage the clamping members, and means coacting with such elongated members for maintaining the clamping members in proper engagement with the rail.

2. A rail chair having a transverse recess adapted to accommodate the base of a rail, the end marginal portions of such chair being provided with longitudinally disposed channels in communication with the transverse recess, clamping members slidably positioned within the channels, each of such channels and the transverse recess being provided with a longitudinally disposed channel, elongated members resting in the longitudinally directed recesses, such members being adapted to operatively engage the clamping members, and means coacting with such elongated members for maintaining the clamping members in their proper engagement with the rail.

3. A rail chair having a transverse recess adapted to accommodate the base of a rail, the end marginal portions of such chair being provided with longitudinally disposed channels in communication with the transverse recess, clamping members slidably positioned within the channels, each of such channels and the transverse recess being provided with a longitudinally disposed channel, elongated members resting in the longitudinally directed recesses, such members being adapted to operatively engage the clamping members, means coacting with such elongated members for maintaining the clamping members in their proper engagement with the rail, and additional retaining means for the clamping members coacting with such clamping members and the chair, such means permitting a limited movement of the clamping members.

In testimony whereof I hereunto affix my signature in the presence of two witnesses.

JEFF N. LAMAR.
